UNITED STATES PATENT OFFICE.

HARRY E. DOERR, OF ST. LOUIS, MISSOURI, ASSIGNOR TO SCULLIN STEEL COMPANY, OF ST. LOUIS, MISSOURI, A CORPORATION OF MISSOURI.

SIDE FRAME.

1,378,221.

Specification of Letters Patent. Patented May 17, 1921.

Application filed March 25, 1920. Serial No. 368,640.

To all whom it may concern:

Be it known that I, HARRY E. DOERR, a citizen of the United States, residing at St. Louis, and State of Missouri, have invented 5 certain new and useful Improvements in Side Frames, of which the following is a specification.

This invention relates to side frames, and particularly to side frames of the pedestal 10 type.

Heretofore pedestal truck side frames have required a special journal box. Accordingly, such a side frame could not be used for replacements of arch bars or the 15 standard type of frame, both of which use Master Car Builders' journal boxes.

Therefore, one object of this invention is to provide a simple and novel pedestal truck 20 side frame which will accommodate Master Car Builders' journal boxes in such a manner that parts of the side frame and journal boxes will coöperate to prevent accidentally relative lateral movement.

Another object is to provide a truck side 25 frame which may be detachably connected to a journal box in a manner to obviate the use of bolts and whereby an emergency fastening is formed should the truck be derailed or lifted from the track by any other 30 part than the axles.

These and other objects are accomplished by means of the arrangement disclosed in the accompanying sheet of drawings, in which—

35 Figure 1 is a fragmentary side elevation of a truck side frame embodying my invention, and shown in normal coöperative position with a Master Car Builders' standard journal box;

40 Fig. 2 is a fragmentary top plan view of the same arrangement; and

Fig. 3 is an end elevation of the same parts.

The various novel features of my invention will be apparent from the following 45 description and the drawings, and will be particularly pointed out in the appended claims.

Referring to the figures of the drawings, 50 it will be noted that I have provided a truck side frame 10 having pedestal jaws 11, the lower ends of which terminate in laterally extending portions 12, which extend toward each other lengthwise of the side frame.

55 These extending jaw portions 12 engage the

sides of the Master Car Builders' journal box 13 intermediate its ends and more particularly intermediate the vertical planes of the bolt lugs 14. As is apparent from the arrangement disclosed in the figures of the drawings, it would be impossible to apply the side frame to the journal box by a relative vertical movement while the jaw extensions 12 are intermediate the journal box bolt lugs 14. Accordingly, to apply the side 65 frame to the journal box when the latter is fixed on the journal, the side frame 10 is moved inwardly with respect to the journal box to a point where the relatively narrow jaw extensions 12 may pass vertically downwardly between the inner journal box bolt lugs 14 and the dust-guard housing 15. With the side frame in this position, the same may be lowered, permitting the jaw 70 extensions 12 to pass vertically downwardly 75 beyond the upper journal box bolt lugs 14, whereupon the side frame may be moved relatively outwardly with respect to the journal box to take its normal operating position.

It will be noted that the side frame 10 is provided with four housing lugs 16 which fit over the outside and embrace the four upper journal box bolt lugs 14. Accordingly, when the journal box 13 and side 80 frame have been moved relatively laterally to a point where the housing lugs 16 may assume the proper position with respect to the box lugs 14, the side frame 10 is lowered into the position shown in Fig. 1 of the 85 drawings to prevent relative lateral movement between the side frame and journal box under normal operating conditions.

These Master Car Builders' journal boxes are provided with raised portions 17 forming side shoulders or bearings 18. I have provided my side frame with oppositely arranged flanges 19 which are intermediate and connect the lugs 16 and which engage or embrace the sides of the shoulders or 95 bearings 18 of the journal box to assist in resisting the action on curves and also on rough or uneven track. Not only will the flanges 19 assist the lugs 16 in overcoming relative lateral movement between the journal box and the side frame, but the flanges 19 will strengthen the lugs and provide a 100 more durable arrangement to overcome the severe service conditions.

It will be noted that the jaw extensions 110

- 12 are spaced from the housing lugs 16 vertically an amount to accommodate the box lugs 14 in applying the frame to and withdrawing the same from the journal box.
- 5 The pedestal jaw extensions 12 act as an emergency fastening for maintaining the connection between the side frame and the journal box, and therefore the wheels and axles, in the event that the truck is derailed.
- 10 or is lifted from the track by any other part than the axles. No bolts or other fastenings of any kind are used to hold the side frame in proper position other than the parts hereinabove specifically set forth; the housing
- 15 lugs 16 embracing the sides of the journal box lugs 14, the flanges 19 embracing the journal box bearings 18, and the pedestal jaw extensions 12 bearing against the sides of the box for holding the same in proper
- 20 relation to the side frame. It will be understood that when it is desired to replace a broken journal box, the same may be done by raising the side frame an amount to properly accommodate the upper journal
- 25 box lugs 14 between the jaw extensions 12 and the housing lugs 16, whereupon the new journal box may be moved laterally inwardly to the point where the housing lugs 16 may move down over the journal box
- 30 lugs 14 and the flanges 19 over the bearing portions 18.

It is my intention to cover all modifications of the invention falling within the spirit and scope of the following claims.

- 35 I claim:
1. A pedestal truck side frame, including pedestal jaws having portions which embrace bolt lugs of Master Car Builders' journal boxes, and having associated portions connecting said other portions longitudinally and embracing bearings on said journal boxes normally to prevent relative
- 40

lateral movement between the side frame and journal box.

2. A truck side frame, including pedestal jaws having portions which engage bolt lugs on Master Car Builders' journal boxes, and having strengthening flanges connecting said portions which engage shoulder bearings on said journal boxes normally to prevent lateral movement between the side frame and journal box.

3. A pedestal truck side frame, including pedestal jaws which embrace bolt lugs on Master Car Builders' journal boxes, and having means intermediate said portions which embrace side shoulder bearings on said journal boxes normally to prevent relative lateral movement between the side frame and journal box, said pedestal jaws also having portions which embrace the sides of the journal box between the bolt lugs thereof for assisting in maintaining the operative position of said side frame and said journal box.

4. A pedestal truck side frame having a plurality of lugs for embracing adjacent bolt lugs on Master Car Builders' journal boxes, and having flanges intermediate certain of said lugs for embracing the shoulder portions on said journal boxes to prevent relative movement between the journal box and side frame.

5. A pedestal truck side frame having four lugs for embracing adjacently arranged bolt lugs of the journal box, and having two flanges connecting certain of said four lugs for embracing shoulders on the journal box normally to prevent relative lateral movement between said side frame and journal box.

Signed at St. Louis, Missouri, this 20th day of March, 1920.

HARRY E. DOERR.
